United States Patent Office

Des. 205,237
Patented July 12, 1966

205,237

COMBINED CAN PUNCH AND BOTTLE OPENER

Cecil L. Moore, 10312 Varnum Drive; and Sidney A. Wilner, 5033 Mindoch St., both of St. Louis, Mo.; and Raymond C. Kastrup, 4060 Highwillow, Florissant, Mo.

Filed Apr. 27, 1965, Ser. No. 84,987

Term of patent 3½ years

(Cl. D44—29)

Fig. 1.

Fig. 2.

Fig. 3.

Fig. 4.

FIG. 1 is a front elevational view of a combined can punch and bottle opener showing our new design;

FIG. 2 is a side view thereof, the opposite side being a mirror image of the side shown; and

FIG. 3 is a rear elevational view thereof; and

FIG. 4 is a sectional view taken generally along the line 4—4 of FIG. 1.

The essential features of our design reside in the portions shown in full lines.

We claim:

The ornamental design for a combined can punch and bottle opener, as shown and described.
